FUSE PLUG

George R. Brown, Bridgeport, Conn., assignor
to General Electric Company, a corporation
of New York

Application December 9, 1931. Serial No. 579,849

2 Claims. (Cl. 200—130)

My invention relates to electrical safety devices and more particularly to fuse plugs.

In the manufacture of fuse plugs considerable difficulty has been experienced in finding a satisfactory means of keying the base, shell and top together so that the turning of the plug during its insertion or removal from a receptacle will not separate these parts and sever the fusible element which is connected between the center contact in the base and the shell. Also, it frequently happens that upon the blowing of a fuse such a high gas pressure is generated in the plug that the top of the plug will be shattered or separated from the other parts of the plug. When the top of the plug becomes separated from the remainder of the plug as it is being removed from a receptacle considerable difficulty may be experienced in removing the shell and base of the plug.

The object of my invention is to provide an improved fuse plug which shall permit of ready inspection of the fusible element at all times and which shall have its component parts so keyed together that the blowing of the fusible element or the frequent insertion or removal of the plug from a receptacle will not cause a separation of the parts.

What I consider to be novel and my invention will be better understood by reference to the following specification and appended claims when considered in connection with the accompanying drawing.

In the drawing, Fig. 1 is a vertical section of the plug; Fig. 2 is an exploded view of the plug shown in perspective from the rear with the top in section; Fig. 3 is a detail view of the rear of the plug in perspective; and Fig. 4 is a perspective view of a section of the top of the plug at right angles to its position in Fig. 2.

In the drawing the fuse plug is indicated generally by the numeral 10 and comprises a top 11, a base 12 and a shell 13. A center contact 14 is mounted in the base and a fusible element 15 is connected at one end to the center contact 14 and at the other end to shell 13. The top 11 is of a transparent material, preferably a glass, having a high fusion point and low coefficient of expansion, such as Pyrex, which will withstand high gas pressures within the fuse plug and will not be easily broken by mechanical strain. The use of such a glass for the top 11 presents difficulties in the molding of the top because it is practically impossible to mold narrow recesses because of the high temperature of the molten glass, which tends to burn any projecting portion 55 of the mold. To overcome this difficulty and at

the same time provide means for keying the top 11 to the base 12, a substantially cylindrical central chamber 16 is provided in the top having a flat side 17 which is better indicated in Fig. 4. The top is provided with a magnifying lens in the window to magnify the break in the fusible element located below this window. The outside of the top 11 is threaded to receive the shell 13 and has a longitudinal groove 18 in which the fusible element 15 is adapted to rest.

Base 12 is of porcelain and has an extension 19 which is substantially cylindrical except for a flat side 20. This extension 19 is adapted to extend within the chamber 16 of top 11 with the flat side 20 in engagement with the flat side 17 within the chamber to key the top 11 and base 12 together to prevent relative rotary movement between the parts. The base is provided with a knob 21 which is substantially square and has sharp edges. An opening 22 extends through the knob 21 and into the central chamber surrounded by the extension 19. Rivet 14 is adapted to be seated in the opening 22 and its inner end expanded to engage a shoulder 23 within the central chamber.

Shell 13 is provided with threads and is of the usual form with the exception that it is provided with an angular shoulder 24 whose inner diameter is substantially the same as the diagonal across the edges of the knob 21 on the base 12. This shoulder 24, as best indicated in Fig. 3, is pressed down so that it is flattened, except for the portions which engage the sharp edges of knob 21, to key the shell 13 to the base 12. Fusible element 15 is connected at one end to the inner side of center contact 14 by solder 25 as indicated in Fig. 1 and is then bent with a portion, including the reduced portion, parallel to the lens window, across the edge of top 11, and extends into the recess 18 on the outside of top. The other end 95 of the fusible element 15 is connected to the shell by being soldered thereto.

In assembly of the fuse plug 10, the center contact 14 is first placed in position in the base 12 and its inner end expanded against the shoulder 23. One end of the fusible element 15 is soldered to the center contact 14 and bent to the desired shape. Base 12 is then inserted in the top 11 with the extension 19 extending within the chamber 16 and the flat side 20 in engagement with the flat side 17 of chamber 16. Shell 13 is then threaded over the outside of top 11 until its end abuts the end of base 12. The angular shoulder 24 is then pressed flat with portions engaging the edges of the knob 21 as best indicated in Fig. 3.

The other end of the fusible element 15 is connected to the shell 13 by soldering or any other means desired. The fuse plug 10 is then completely assembled and ready for use.

- 5 From the foregoing it may be seen that a fuse plug is provided with a top of material which will withstand high gas pressures which are frequently generated on the blowing of the fusible element and which is not likely to be damaged by mechanical strains. Also, the method of keying the base and top together is such as to reduce the likelihood of damage by mechanical strains or the blowing of the fuse. The keying of the shell to the base is positive and thus reduces to a minimum the likelihood that the shell should be separated from the remainder of the fuse plug or that there should be sufficient relative motion to sever the fusible element connected between the base and shell.
- 10 What I claim as new and desire to secure by Letters Patent of the United States is:
- 15 1. A fuse plug comprising a top of glass having a high fusion point threaded on the outside and having a central chamber substantially cylindrical with one flat side extending a portion of its length, a base of insulating material with a substantially cylindrical portion at one end extending
- 20 25 within the chamber of the top and having a

flat side in engagement with the flat side of the chamber and a knob with sharp corners on the other end, a center contact secured in said base, a fusible element with one end connected to the center contact, and a metallic shell threaded on said top and having a shoulder engaging the sharp corners of said knob on the base and electrically connected to the other end of the fusible element.

2. A fuse plug comprising a top of glass having a high fusion point threaded on the outside and having a central chamber substantially cylindrical with one flat side extending a portion of its length and a longitudinal groove extending on the outside from the bottom to near the top, a base of insulating material with a substantially cylindrical portion at one end extending within the chamber of the top and having a flat side in engagement with the flat side of the chamber and a square knob on the other end, a center contact secured in said base, a fusible element with one end connected to the center contact and seated in the groove of the top, and a metallic shell threaded on said top and having an angular shoulder engaging the corners of said knob and electrically connected to the other end of the fusible element.
